(57) CLAIM

The ornamental design for a textured fan housing, as shown and described.

DESCRIPTION

FIG. 1 is a perspective view of a textured fan housing showing my new design;

FIG. 2 is a side view thereof (views from the other side, top and bottom thereof are the same);

FIG. 3 is a perspective view of a second embodiment thereof;

FIG. 4 is a side view of the second embodiment (views from the other side, top and bottom thereof are the same);

FIG. 5 is an enlarged plan view of a portion of the surface ornamentation of the textured surfaces of the fan housings shown in FIGS. 1-4; and,

FIG. 6 is a sectional view as taken along line 6—6 of FIG. 5.

The broken line showing environmental structure in FIGS. 1 and 5 is for illustrative purposes only and forms no part of the claimed design.
